Attorney

UNITED STATES PATENT OFFICE

DONALD D. WHITACRE, OF WAYNESBURG, OHIO

CUTTER

Application filed September 7, 1929. Serial No. 391,070.

This invention relates to cutting machines and more particularly to apparatus for cutting tile or the like from a moving stream of plastic material.

The machine which is illustrated in the drawings and described herein is particularly adapted to cut off individual tile from a continuously moving stream of clay which has been extruded through a die in well known manner and it is among the objects of my invention to provide a machine for cutting tile which have portions of their cut ends lying in different planes; to provide a tile cutter which may be adapted either to cut tile having parallel plane end surfaces or tile which have portions cut out of one end; to provide a tile cutter which will cut a continuously moving stream of clay into tile having end surfaces lying partly in one plane and partly in another to cut the clay stream to form notches in either the ends of body of the resulting blocks; and to provide a rugged and efficient machine for cutting tile or the like.

A preferred form of my invention is illustrated in the drawings in which

Fig. 1 is a side elevation of my cutting machine in position to cut tile from a stream of clay extruded from a standard form of extruder; Fig. 2 is a section on line 2—2 of Fig. 1; Fig. 3 is an enlarged fragmentary view of the cam mechanism; Fig. 4 is a fragmentary section taken on line 4—4 of Fig. 3; and Fig. 5 is a perspective view of one form of tile adapted to be cut by my cutter.

The extruding mill 1, shown diagrammatically in Fig. 1, may be of any suitable type and is preferably equipped with a die through which the moist plastic clay is forced to give it the shape desired. When making the tile T illustrated in Fig. 5 the die 2 will be shaped to form the longitudinally extending apertures, shells and webs and the tile will be extruded as a continuously moving stream of clay, having the desired cross section. To form the individual tile shown in Fig. 5 the stream of clay must be cut into pieces of proper length and shape. It is exceedingly advantageous to perform this cutting operation while the clay stream

is in motion and my apparatus provides a simple and efficient apparatus for so doing.

As the extruded clay stream leaves the die 2 it passes over the supporting roll 3 and then to the cutting table 4. Secured to the under side of table 4 are the downwardly extending side members 5 which are adapted to rest on and roll over the flanged wheels 6. The wheels 6 are mounted on fixed axles 7 which are secured to the frame 8. The axles 7 are so spaced that the side members 5 are always supported on wheels 6 in the well known manner.

Extending between the right hand end (Fig. 1) of the table 4 and the conveyor belt 9 is a thin plate 10 which serves to support the cut tiles 11 as they move along between the table 4 and the belt 9.

A table return lever 12 is pivotally supported on the bracket 13, which may be attached to one of the side members 5, and is connected to the frame 8 through slid able links 14 and 15. This link connection permits the table to roll freely on the wheels 6 to the end of its travel and be manually returned to its starting position by the lever 12.

The cutting mechanism proper consists of a pair of U-shaped yokes 16 which are pivoted to the brackets 17 secured to the side member 5. The yokes 16 are connected together by suitable cross members such as 18, 19 and 20 forming a rigid structure. The tile are cut by the cutting wires 21 which are strung across between the cross members 18 and are spaced apart the proper distance to cut the size of tile desired. They may be maintained at the desired tension by means of adjusting screws 22 and are adapted to enter the slots 23 in the table 4 at the end of their cutting movement.

As is seen from Fig. 5 the tile has a substantially rectangular piece cut out on one side. To cut this piece 24 I provide auxiliary cutting wires 25 which are strung across the open ends of the yokes or bows 26. These bows 26 are mounted for swinging movement in bearing blocks 27 and are connected together adjacent their lower ends by members 28. These connecting

members 28 are pivotally secured to each of the bows 26 so that they will all swing together. The bearing blocks 27 are mounted on the longitudinal members 20 and it will be seen that the main cutting wires 21 and the auxiliary cutting wires 25 are supported by a rigid structure which is pivoted to the brackets 17 and is adapted to swing about this pivot toward and away from the table 4.

A cam roller 29 is mounted on a downwardly extending frame 30 which is secured to the member 28. The roll 29 is adapted to travel in and be guided by a curved upwardly projecting cam track 31. The bracket 32 which supports the cam track 31 may be secured to the top of the table 4 in any desired manner and is best illustrated in Figs. 3 and 4. The track 31 is curved to correspond with the path of the roll 29 as it swings about the pivotal axis A of the bracket 17 and is provided with two adjacent track portions one of which, 33, guides the roll 29 in its downward movement and the other of which, 34, guides its upward movement. The curved bottom portion 35 of the cam track 31 serves to throw the roll 29 over from track 33 to track 34 as the roll is moved downwardly and the upper curved portion 36 throws the roll back from the track 34 to the track 33 on its upward movement. The exact shape of the cam tracks 33 and 34 and the curved end portions 35 and 36 determine the shape of the cut, as will be clear from the following explanation of the preferred method of operating my cutter.

When the extruding machine 1 is in operation, a continuous stream of plastic clay 40 is forced through the forming die 2, over the roll 3 and across the table 4 and plate 10 to the conveyor belt 9. As the stream of clay moves the friction between it and the table 4 will be sufficient to cause the table 4, together with the cutting mechanism, to be moved along on the wheels 6 at the same speed as the clay stream. The movement of the table 4 is limited, however, by a stop 37 and when the table reaches this stop, this clay stream will simply slide over its surface and on to the conveyor 9. Assuming that the cutting mechanism is swung upwardly on its pivoted supports so that the cutting wires are above the clay stream and the table 4 is against the stop 37, the operator swings the return lever 12 which slides the table back against the movement of the clay stream until it reaches the position shown in Fig. 1. As soon as the lever 12 is released the table starts to move with the clay stream and the operator then pulls down the cutting mechanism until it is in the position shown in Fig. 2, and then lifts it up until it is up out of the path of the clay stream. This lowering and lifting of

the cutting mechanism must be completed before the table reaches the end of its travel, as there should be no relative movement between the clay stream and the cutting wires during the cutting operation.

The main cutting wires 21 travel up and down in the same path. On their down stroke they make the vertical cuts indicated at 38 in Fig. 1, and on their upstroke they pass back through the cut 38 without further cutting. At the beginning of the down stroke of the cutting mechanism, the roll 29 is at the top of the track 33 and on the down stroke the wires 25 make the vertical cuts indicated at 39 in Fig. 1. As the roll 29 comes to the bottom of the cam, it is thrown to the left into the track 34 by the curved portion 35 and makes the substantially horizontal cut 40. The radius joining cuts 39 and 40 will depend upon the curvature of the portion 35 of the cam track.

The upward guiding track 34 is so positioned that, on the upward movement of the cutting mechanism, the auxiliary cutting wires 25 will move in the cuts 38 made by the main cutting wires 21 on their down stroke and the top curved portion 36 is so located that it will throw the roll 29 back into track 33 after the wires 25 are clear of the clay stream.

In the apparatus illustrated in the drawings, I have shown four main cutting wires and four auxiliary cutting wires and from the above description it will be seen that each complete movement of the cutting mechanism from its upper position to the bottom of its stroke and back to the starting point will cut three complete tiles. Any desired and practical number of cutting wires may be employed depending on the consistency of the clay, size of tile to be cut, etc.

The cut tiles will be pushed along to the conveyor belt 9 by the oncoming clay stream. The conveyor 9 may move at a slightly higher speed than the clay stream to separate the cut tiles and facilitate the removal of the cut out pieces 24. These pieces 24 may be put back in the extruding machine so there will be no clay wasted.

Although I have illustrated and described herein a machine for cutting a particular shape of clay tile, it will be clear to those skilled in the art that my invention may be adapted to cutting other shapes and materials than those specifically mentioned without departing from the spirit of my invention, and I do not limit myself in any manner other than by the appended claims.

I claim:

1. In an apparatus for cutting a moving stream of plastic material into similarly shaped pieces the combination of a table adapted to move with said material, and cutting mechanism adapted to move with said

table comprising means for making spaced apart cuts through said stream of material and means for simultaneously making other cuts in said material starting in spaced relation to said first named cuts and extending to said first named cuts.

2. Apparatus for cutting a mass of plastic material into sections comprising a plurality of cutting wires, means for moving some of said wires downwardly through said plastic mass and upwardly through the slot made on their downward movement, means for causing others of said wires to enter said mass at points removed from the slots cut by said first named wires, pass partially through said mass and be removed through the slots cut by said first named wires.

3. In apparatus for cutting plastic materials the combination of a cutting wire, means for moving said cutting wire through said plastic material, a second cutting wire and means for moving said second cutting wire through said plastic material for a portion of its movement and through the slot cut in said material by the first named wire for a portion of its movement.

4. In apparatus for cutting plastic materials a pair of cutting wires, means for moving one of said wires downwardly through said material, means for simultaneously moving the other of said wires through said material in a path removed from the path of travel of said first named wire and means for guiding said second named wire into the path of travel of said first named wire.

5. In apparatus for cutting plastic materials a cutting wire, means for moving said wire downwardly through said material and upwardly through the cut made on the downward movement, a second cutting wire, means for moving said second wire downwardly and laterally through said material and upwardly through the cut made on the downward movement of said first named wire.

6. Apparatus for cutting plastic material comprising a cutting table, means for supporting a plurality of cutting wires above said table, means for moving some of said wires in parallel paths, a cam secured to said table, a cam follower secured to said wire supporting means and adapted to contact with said cam to cause others of said cutting wires to move in paths partly separate from and partly coincident with the paths of said first named wires.

7. Apparatus for cutting plastic materials comprising a cutting table, a wire supporting frame pivoted to said table, a plurality of cutting wires mounted on said frame, a plurality of auxiliary cutting wires, means for supporting said auxiliary wires on said wire supporting frame to permit movement of said auxiliary wires relative to said frame, and cam means adapted to control the move-

ment of said auxiliary wires relative to said wire supporting means.

8. Apparatus for cutting tile from a moving stream of plastic material comprising a cutting table, means for supporting said table to allow it a limited movement in the direction of travel of said stream of material, means for causing said table to move in a direction opposite to that of the stream of material, means secured to said table and movable therewith for cutting said stream of material into tile, and auxiliary cam guided cutting means for cutting out portions of said tile adjacent the cuts made by said first named cutting means.

9. Tile cutting mechanism comprising a table, a frame pivotally supported on said table, cutting wires pivotally suspended from said frame and means for directing and swinging said wires relative to said frame.

10. Tile cutting mechanism comprising a table movable with the clay stream, a frame pivotally mounted on said table and swingable about an axis parallel to said clay stream, cutting means pivotally suspended from said frame and swingable about an axis normal to said clay stream, a track member secured to the table and curved about the pivotal axis of the frame as a center, and a roller connected to said means guided in said track for directing the movement of said means.

11. In an apparatus for cutting a mass of plastic material into sections, a cutting wire, means for moving said wire downwardly through said material and upwardly through the cut made on the downward movement, a second cutting wire, means for moving said second wire downwardly and laterally through said material and upwardly and out of said mass.

12. Apparatus for cutting a mass of plastic material into sections comprising a plurality of cutting wires, means for moving certain of said wires in one direction into said plastic mass and out through the slots made on said first named movement, means for causing others of said wires to enter said mass at points spaced from the slots cut by said first named wires and to move downwardly and laterally thereinto, said second named wires being moved in another direction to effect the removal thereof from said mass.

In testimony whereof I hereunto affix my signature this 27th day of August, 1929.

DONALD D. WHITACRE.
